UNITED STATES PATENT OFFICE

MAURICE CHARLES, OF COURBEVOIE, FRANCE

SAFETY SWITCH

Application filed August 28, 1928, Serial No. 302,681, and in France September 27, 1927.

My invention relates to safety switches of the type which, first, breaks the circuit including the battery and starter of an automobile, and, second, renders the ignition circuit inoperative at the same time, by grounding the magneto. These two operations are effected automatically if the automobile turns over.

Briefly outlined, my invention consists of a switch of the character indicated comprising a receptacle of an insulating material containing a certain quantity of mercury in which is disposed a plunger floating thereon likewise of insulating material adapted to be lowered by manual controlling means in such a way that the level of mercury rises around the said floating plunger. In the said receptacle are provided three metallic terminals, one connected to the ground (consisting of the frame of the vehicle), the second to battery circuit, and the third to the magneto ground terminal.

The whole is arranged in such wise that when the vehicle is stopped, the battery circuit will be normally open and the magneto grounded. Thus, if, during stopping of the vehicle, the starter pedal be pushed in, the motor cannot be started until the switch has been operated. When the switch is brought into play the floating plunger descends to close the battery circuit at that point and the ground is simultaneously removed from the magneto. Obviously the reverse takes place when the plunger is allowed to rise.

In the case of the turning over of the vehicle accidentally, the mercury automatically flows to the other end of the switch and not only is the battery circuit opened but also the magneto ground is re-established, so that risks of fire are prevented.

The following description taken in connection with the accompanying drawings given by way of example will enable the invention to be well understood by those skilled in the art.

In the drawings—

Fig. 1 is a sectional view of my switch taken along the line 1—1 of Fig. 2;

Fig. 2 is a section along the line 2—2 of Fig. 1; and

Fig. 3 is a broken horizontal section along the line 3—3 of Fig. 1.

Referring to the drawings, my switch consists of a cup *a* of moulded insulating material provided with a cover *b* and filled to about $\frac{1}{5}$ of its capacity with mercury *c*.

In the body of the cup *a* are buried two metallic rings *d* and *e*, whose surfaces are flush with the wall of the cup and which are respectively connected to the battery terminal of the starter circuit by means of a rod *f* and a thimble *g*, and to the frame of the chassis *i* by means of a rod *h*.

On the mercury floats a plunger *j* of insulating material provided with four grooves *k* in which the mercury can rise along the wall of the cup when the plunger *j* is pushed down.

A terminal *l*, provided with a spring blade *m* at its lower part is mounted on the cover and connects to the ground terminal of the magneto. Said spring is arranged in a way to be able to come into contact with a cam *n* rigid on a shaft *o*, turning in a metallic bearing *p* provided in the body of the cup *a* and in electrical connection with the frame *i*.

In the position shown in Fig. 1 the starter circuit is open, the two rings *d* and *e* being insulated with respect to each other. The magneto is grounded by means of the blade spring *m* which comes into contact with the cam.

For opening the circuit of the magneto and closing that of the starter, a button *q* on the shaft *o* is turned half a revolution.

The cam *n* leaves the spring blade *l*, opening the circuit of the magneto to the ground, and causes pressure on the piston *j* which moves to the position shown in dotted lines in Fig. 2. The said plunger is pushed into the mercury *c* which rises in the grooves *k* to a point above the ring *d*.

The circuit of the starter is closed at the same time, through thimble *g*, rod *f*, ring *d*, mercury *c*, ring *e*, rod *h* and the frame of the chassis *i* and if the vehicle turns over the mercury falls back to the side where the spring *m* is and consequently the circuit between the two rings *d* and *e* is broken. At

the same time the mercury comes in contact with the cam *n* and the spring *m* thus grounds the magneto thus automatically preventing all risks of fire.

5 I preferably employ a latching arrangement such as that disclosed in my French Patent No. 609,533 of January 19, 1926, for locking my switch in circuit open position.

Obviously many modifications may be 10 made in my device without departing from the spirit of the invention as comprehended within the scope of the appended claims.

For example, instead of grounding the magneto, the contact blade may be adapted 15 to open a Delco battery ignition circuit.

Having thus described my invention what I claim as new and desire to secure by Letters Patent is:

1. In a safety switch of the type described, 20 the combination of a magneto ground terminal, a battery circuit ground terminal, fluid contact means connected in series with said last-mentioned ground terminal and manually operable means for simultaneously disconnecting said magneto ground terminal and closing said fluid contact means, said battery ground terminal being adapted to be disconnected and said magneto ground terminal connected upon inversion of said 25 switch.

2. In a safety switch of the type described, 30 the combination of a vertical cup of insulating material, a battery circuit ground terminal, a contact ring within said cup connected to said terminal, a second terminal connected to the ground, a contact ring for said second terminal within said cup, mercury in said cup in contact with said last ring only, a magneto ground terminal at the other end of said 35 cup with respect to said first terminals, a plunger of insulating material in said cup, and manually operable means for simultaneously causing said plunger to descend and disconnecting said magneto ground terminal 40 from the ground.

3. In a safety switch of the type described, 45 the combination of a cup of insulating material, a battery circuit ground terminal, a contact ring within said cup connected to said terminal, a second terminal connected to the ground, a contact ring for said second terminal within said cup, mercury in said cup in contact with said last ring only, a magneto ground terminal at the other end of said cup 50 with respect to said first terminals, a plunger of insulating material in said cup, a manually operable cam in contact with the ground adapted to depress said plunger when moved to its lower position, and a spring contact on 55 said magneto terminal adapted to contact with said cam when said cam is in its upper position.

4. In a safety switch of the type described, 60 the combination of a cup of insulating material, a battery circuit ground terminal, a con-

tact ring within said cup connected to said terminal, a second terminal connected to the ground, a contact ring for said second terminal within said cup, mercury in said cup in contact with said last ring only, a magneto ground terminal at the other end of said cup with respect to said first terminals, and manually operable means for simultaneously raising the level of said mercury and disconnecting said magneto ground terminal from the ground. 75

5. In a switch of the type described, the combination of a battery circuit ground terminal, a magneto circuit terminal, manually controlled means for establishing and opening a ground circuit for said magneto terminal and a mercury switch adapted to open and close a ground circuit to said battery terminal controlled by operation of said means, said mercury switch being adapted to automatically open circuit to said battery terminal and close the circuit of said magneto terminal when said switch is inverted. 80

6. In a switch of the type described, the combination of a casing of insulating material, a battery circuit ground terminal secured to said casing, a magneto circuit ground terminal secured to said casing, a ring within said casing connected to said battery terminal, a second ring within said casing disposed in spaced relation with respect to said first ring, means for grounding said second ring, mercury in said casing, a piston of insulating material adapted to float on said mercury, a spring blade attached to said magneto ground terminal and manually operated means normally for depressing said piston in said mercury for the purpose described. 85

7. In a switch of the type described, the combination of a casing of insulating material, a battery circuit ground terminal secured to said casing, a magneto circuit ground terminal secured to said casing, a ring within said casing connected to said battery terminal, a second ring within said casing disposed in spaced relation with respect to said first ring, means for grounding said second ring, mercury in said casing, a piston of insulating material adapted to float on said mercury, a spring blade attached to said magneto ground terminal, a rotatably mounted metallic shaft in said casing connected with the ground and a cam on said shaft adapted to interconnect said spring and said metallic shaft and to depress said piston in said mercury when moved away from said spring. 100

8. In a switch of the type described, the combination of a casing of insulating material, a battery circuit ground terminal secured to said casing, a magneto circuit ground terminal secured to said casing, a ring within said casing connected to said battery terminal, a second ring within said casing disposed in spaced relation with respect to said first ring, means for grounding said second ring, 105

mercury in said casing, a piston of insulating material adapted to float on said mercury, a spring blade attached to said magneto ground terminal, manually operated means connecting said spring with the ground when the motor is stopped and adapted to depress said piston in said mercury and a plurality of longitudinal grooves formed in the periphery of said piston whereby said mercury automatically opens the ground connection to said battery terminal and grounds said magneto terminal when said switch is inverted.

9. In a switch of the type described, the combination of a casing of insulating material, a battery circuit ground terminal secured to said casing, a magneto circuit ground terminal secured to said casing, a ring within said casing connected to said battery terminal, a second ring within said casing disposed in spaced relation with respect to said first ring, means for grounding said second ring, mercury in said casing, a piston of insulated material adapted to float on said mercury, a spring blade attached to said magneto terminal, a metallic rotatably mounted shaft in said casing, connected with the ground, a cam on said shaft adapted to interconnect said spring and said metallic shaft and to depress said piston in said mercury when moved away from said spring and a plurality of longitudinal grooves formed in the periphery of said piston whereby said mercury automatically opens the ground connection to said battery terminal and grounds said magneto terminal when said switch is inverted.

In testimony whereof I have signed this specification.

MAURICE CHARLES.
